UNITED STATES PATENT OFFICE

NORMAN M. STEPHENSON, OF LOS ANGELES, CALIFORNIA

REFILLABLE CARTRIDGE FUSE

Application filed June 19, 1929. Serial No. 371,985.

This invention relates generally to electrical fuses, and particularly to electrical fuses of the type commonly known as "cartridge" fuses. These have a tubular, non-conductive shell, containing a fusible element, and are adapted to be inserted between two points in an electric circuit. Cartridge fuses of this type are usually inserted in the circuit, on the switch block, or on a separate fuse block, which is provided with spring clip contact terminals adapted to removably engage contact points on the opposite ends of the shell.

More specifically my improvement pertains to cartridge fuses of the refillable type, wherein the shell or casing is adapted to contain a standardized replaceable fuse element, or refill, which may be easily renewed from time to time as occasion requires. As fire hazards are increased by the overloading of electric wiring, due to the use of fusible elements having more than a safe load capacity, it is of great importance that refillable cartridge fuses, of this type, be not only designed to perfectly insulate against fire upon "blowing out", but also to prevent overloading of the circuit by the use of unauthorized, higher capacity, fusible elements. It is a particular feature of my invention that my construction permits the accomplishment of both of these objects.

Heretofore, in fuses of this type, it has been possible to insert more than a single fuse element in a tube designed for a given maximum capacity, resulting in danger of overloading of a circuit designed to be fused at a given limit. It has also been possible to employ, in a fuse designed for a given maximum capacity, an element of larger capacity, resulting similarly in danger of overloading of the circuit. According to my invention, the type of construction is such that a fuse of a given maximum capacity can receive but a single fusible element, designed for that capacity, and under no conditions can an element of larger capacity, or two elements of the proper capacity, be inserted in the shell to produce a fuse having more than the rated capacity. In effecting this object I provide the fuse either with a "refill", which is made up or assembled at the

factory and comprises a carrier and an element, or with a carrier in which only the element need be replaced. The design is such that the size of a "refill" of a given capacity corresponds to the inside diameter of the cartridge shell into which the element carrier is to be inserted. In this manner likelihood of inserting a larger refill is avoided, each tube being capable of receiving a "refill" of but one maximum capacity. Each element carrier in turn is gauged to receive but a single element of given maximum capacity.

My arrangement is such that a minimum of replaceable parts is employed, and the operation of supplying or inserting a new "refill" is extremely simple. Each tube is provided at its opposite ends with caps, or ferrules, which are easily removable, by hand, to permit removal of a burned-out element and the insertion of a new "refill". The construction is such as to also permit the use of a "refill" which may be filled with non-inflammable powder, if the user prefers that type of fuse. Also, provision may be made for viewing the element from the outside of the tube to indicate the condition of the fuse.

It is also an object of the invention to provide a fuse in which means for connecting the element in circuit presses against the element, the pressure therebetween increasing if the fuse becomes heated, so that a better contact is formed between said means and said element.

A further object is to provide a fuse in which any arc formed on the blowing of the element will be so limited and confined that no damage to the fuse will result therefrom.

Another object is to provide a fuse in which any heat generated within the fuse is prevented from materially affecting the ends thereof.

The invention will be fully understood from the following description, taken in connection with the accompanying drawings, in which—

Fig. 1 is an elevational view of a fuse of the knife-blade type;

Fig. 2 is a section taken on line 2—2 of Fig. 1;

Fig. 3 is a section taken on line 3—3 of Fig. 2;

Fig. 4 is a section taken on line 4—4 of Fig. 2;

5 Fig. 5 is a face view of a lock-washer employed;

Fig. 6 is a face view of a lock-washer used in connection with the washer shown in Fig. 5;

10 Fig. 7 is a perspective view of the element carrier used in connection with the fuse shown in Figs. 1 and 2;

Fig. 8 is a longitudinal section of a ferrule-type of fuse, the ends, or contact points, 15 of which are adapted to be held between circular spring clips on the fuse block;

Fig. 9 is an elevational view of a fuse of the knife-blade type, provided with an observation aperture;

20 Fig. 10 is a section taken on the line 10—10 of Fig. 9, one end being shown in section and one end partly in elevation;

Fig. 11 is a section taken on the line 11—11 of Fig. 10;

25 Fig. 12 is a perspective view of the element carrier employed in Figs. 9 and 10;

Fig. 13 is a longitudinal section through a 30 fuse of the knife-blade type, showing a modified form of "refill", one end being shown in section and one end partly in elevation; and

Fig. 14 is a section taken on line 14—14 of Fig. 13.

In the drawings, referring particularly to Figs. 1 to 7, inclusive, the numeral 20 designates a tubular cartridge shell, which is externally threaded on its opposite ends to receive internally threaded ferrules 21. The tube 20 may be made of fibrous, non-conductive material, and the ferrules 21 of brass or 40 other suitable metal, provided with a knurled portion 22 to facilitate screwing on the cartridge tube.

The element carrier comprises a cylindrical non-conductive block 23, and a cylindrical non-conductive tube or sleeve 24 which slips over the block 23 to form the carrier unit, which is adapted to be slipped into the cartridge tube 20. The carrier block 23 is preferably cylindrical in form, and is provided on two opposite faces with longitudinal slots or grooves 25 adapted to receive a fusible element 26. The slots 25 are preferably of the same width and depth as the width and thickness of the fusible element of the desired and authorized capacity, and the tube 24 may have a sufficiently close fit over the block 23 to prevent the insertion of more than one element of a given capacity, or of a single element of a larger capacity. The carrier block 23 is provided centrally with a transverse aperture 27, extending cross-wise between the slots 25 on the opposite side of the block. The space afforded by the aperture 27 constitutes a primary expansion chamber permitting of the expansion of gases, caused by

the melting of the fusible element upon "blowing-out", and the grooves 25 on the side of the block, opposite to that in which the fusible element is placed, serve as passages or vents connecting the aperture 27 with the 70 spaces at each end of the shell which constitute secondary expansion chambers, to further accommodate the expanded gases. The fusible element 26 is placed in the grooves 25, to extend across aperture 27, and the ends 75 are then bent or folded transversely across the ends of the carrier block 23, and the carrier then inserted in the tube 24, as shown, for example, in Fig. 2.

In each case the refill is shorter than the 80 inside length of the shell 20, to provide gas expansion chambers; the aperture within the carrier block being the primary expansion chamber and those at the ends being the secondary expansion chambers. The most intense heat is generated in the primary expansion chamber.

The circuit through the fusible element is carried by means of the conductors or members 28, which extend longitudinally of the tube from the opposite ends of the carrier block 23. The inner ends of the conductors 28 are preferably enlarged, as at 29, to afford a contact portion adapted to engage the ends of the fuse elements resting on the ends of the carrier block 23. The outer ends of the conductors extend through the ferrules 21 and terminate in blade portions 30, which are adapted to be engaged by the spring clip terminals on the fuse block. The blade portions 30 are shouldered, as at 31, to receive the washers 32 and 33 which are pressed or shrunk on the blade, against the shoulder, to afford a snug fit. The inner washer 33 is provided with circumferential ears 34 which seat in notches in the ends of the shell 20, to prevent turning of the blades relative to the shell. After the ferrules are slipped on the blades 30, a small portion of the blade may be struck outwardly to form nibs 37 for holding the ferrules relatively rotatable on the blades. In replacing the fusible element one or the other of the ferrules 21 is unscrewed, whereupon the conductor 28 may be withdrawn with the blade and the refill is then free to be dropped or slipped out. A new refill or the same carrier with a new element, is slipped in place within the shell, the conductor 28 is inserted in place, and the ferrule then screwed onto the shell to hold the parts in position.

The inner diameter of shell 20 is of a fixed dimension for a given size refill; that is, the inner diameter of the tubes will vary according to a specified amperage of the fusible element to be employed. The sleeve 24 is similarly of fixed dimension for a given size fusible element, so that, if the complete refill is replaced, all danger of having the line 130

fused incorrectly due to the insertion of an improper element is avoided.

In the knife-blade type of fuses, the caps 21 are fixed against longitudinal movement relative to the terminal 30 which is integral with the conductor or member 28, so that when the cap is screwed onto the end of the shell 20, members 28 press against the ends of the element 26. Thus, when any heat is generated by the fuse, the members 28 being metallic will expand and their pressure against the element will increase so that a better contact with the element is formed. Similarly, expansion of the carrier 23 will 15 better this contact.

Heat within the fuse will also have the effect of causing the insulating shell 20 to dry out and shrink or contract. Thus, the members 28 would be caused to bear still 20 more tightly against the element.

In the ferrule type of fuse, shown in Fig. 8, the contact members 36 being formed integrally with the caps 35, a similar result is obtained.

When an element blows, the gas generated thereby first expands in the primary chamber in the carrier 23 and from there passes to the secondary chambers at the ends of the shell through vents on the side of the carrier 25 opposite to the element. Thus, the gas is drawn away from the element and severe arcing is prevented, and the end portions of the carrier 23 deflect the path of the gas away from the members 28. Because of this, no 30 damage will result to any part of the fuse from arcing after a blow.

In Fig. 8 the construction is essentially the same as that in Figs. 1 to 7, with the exception that in this case the conductors are 40 formed as an integral part of the ferrules. In this form the ferrules 35 are in the form of closed caps, and the conductors 36 are directly connected to the inside surface of the end faces of the ferrules. The ferrules themselves afford closures for the ends of the shell, so that no washers need be employed. This form of fuse, commonly known as the 45 ferrule type, is adapted to be inserted between circular spring clips mounted on the fuse block.

In Figs. 9 to 12 I have shown a fuse of the knife-blade type in which a slightly modified form of element carrier is employed. In this form the element carrier consists of a single block 38 provided on opposite sides with longitudinal slots or recesses 39 adapted to receive the fusible element 40. A circumferential or bridge portion 41 of the carrier block 38 extends across one or both of the 55 grooves 39, and the fuse element 40 is held in position in the slots by means of this bridge or circumferential portion of the block. The portion 41 of the block in effect accomplishes the purpose accomplished in the form first described by the tube 24. The diameter of

the carrier block 38 is such as to closely engage the inner surface of the shell 20. As in the form previously described, the carrier block 38 is provided with a transverse open portion 42 to allow for gas expansion upon 70 melting of the fusible element, and the recesses or grooves 39, on the side of the block, opposite to those in which the fuse is placed, serve as communicating passages or vents between the space 42 and the secondary expansion chambers at the ends of the shell 20. This carrier block may be made of glass, or other transparent non-conducting medium, so that the fuse element 40 may be viewed 75 from the outside of the shell 20 through an aperture 43. Also, as in the forms previously described, the internal diameter of the shell is of fixed or regulated size for a given maximum fuse capacity, and the carrier blocks are similarly gauged to receive an element of predetermined maximum capacity. The advantages of non-replaceability, and the avoidance of interchangeability of fuse elements of different sizes, therefore obtain in 80 this form of carrier block and tube construction just as in the forms previously described.

While in the form shown in Figs. 1 to 8, the width and depth of the grooves 25, when the block 23 is inserted in the tube 24, limit the size of fusible element which may be 85 used, in the form shown in Figs. 9 to 12 the apertures 39a accomplish the same purpose. In this case the bottom face of the portion 41 is spaced from the bottoms of the grooves 39 a distance equal to the thickness of a fusible element of proper size and grooves 39, as well as apertures 39a, are of the proper width to accommodate a fusible element of proper 90 width.

In Figs. 13 and 14 I have shown a fuse of the knife-blade type, similar to that shown in Figs. 1 to 7 and Figs. 9 to 12, in which another somewhat modified form of element carrier is provided. In this form, the element carrier 44 consists of a cylinder closed at one end and provided with a removable cap 44a. The end wall 44b and cap 44a are provided with slots or openings 45 through which the fusible element 46 may be inserted, and the ends bent down as shown. The 105 slots may be positioned on diagonally opposite sides of the cylinder, so that the fusible element extends diagonally across the bore of the tube. Small apertures 45a may be provided in the ends in connection with slots 45 to permit the escape of gases on blowing-out of the fuse. The carrier tube or cylinder 44 may be filled with a non-combustible powder 48. The powder is of insulating 110 quality, such as is commonly used for fuse filling purposes. The element carrier is of a diameter such as to afford a sliding fit in the shell 20, and may be made of glass, or other non-conductive transparent medium, to 115 permit the observer to view the cylinder 120 125 130

through the aperture 43 in the shell wall. In this case, upon explosion of the element, the powder will be discolored, and the observer will be able to note instantly which fuse of a number of fuses has been burned out and when replacement is needed. If powder is not used, the glass will be discolored. In other respects the construction is similar to that described in connection with Figs. 1 to 7 and Figs. 9 to 12. In this case the areas of slots 45 control the maximum size of the fusible element which may be used. As in the forms previously described, the inside diameter of the cartridge tube, for a fuse of given maximum capacity, is fixed or regulated, so that possibility of confusion between elements of different sizes is avoided. As in the previous forms, the element carrier is gauged to receive but a single element of given maximum capacity, and there is no possibility of over-fusing the line.

In all of the forms described the element carrier is shorter than the cartridge tube into which it is inserted. Expansion chambers 47 are thus provided between the ends of the carrier and the closed ends of the tube. These chambers communicate through the element retaining slots with the expansion chamber on the inside of the element carrier. Ample space is thus afforded to allow for gas expansion when the fuse is blown.

The contact members 28 are made of a material having a substantially greater conductivity than the material of which the element is made. Thus, when the fuse is running under a heavy load, no such heat will be generated in the contact members 28 as will be generated in any part of the element. By virtue of this fact, and because the element is relatively short and the contact members 28 extend a substantial distance into the shell, the heat generated in the element is restricted to the central portion of the shell at a distance from the ends thereof. For this reason, the ends of the shells, which are the weakest portions thereof, are protected. Also the points of contact between the contact members and the element are at a substantial distance from the ends of the shell so that any heat generated at those points will not materially affect said ends.

By having such a short element with the adjacent ends of the contact members 28 nearer together than otherwise would be the case, the chance of arcing between said adjacent ends, when the fuse blows, might be greater, were it not for the fact that the carrier constitutes a barrier between the adjacent ends of the contact members, and ample protection against such arcing is provided.

The foregoing detailed description has been given for clearness of understanding only, and no unnecessary limitations should be understood therefrom, but the appended claims

should be construed as broadly as permissible in view of the prior art.

What I regard as new, and desire to secure by Letters Patent, is—

1. A fuse comprising, in combination, an insulating shell, a fuse element mounted within said shell, and elongated rigid expandable members occupying a greater portion of the length of said shell than said fuse element adapted to increase their length on the increase of the heat within the fuse, each member having one end fixed to the end of said shell and having its other end abutting against one end of said element, the expansion of said members due to heat thereby causing them to bear more tightly against said element. 70 75 80

2. A fuse comprising, in combination, an insulating shell, a relatively short carrier mounted within said shell and spaced from the ends thereof, a fuse element mounted on said carrier and having its ends bent transversely across the ends thereof, and a pair of rigid expandable members fixed to the respective ends of the shell and extending inwardly thereof to clamp the ends of said element against the ends of the carrier, the expansion of said members due to heat causing them to bear more tightly against said element. 85 90 95

3. A fuse comprising, in combination, an insulating shell open at the ends, a carrier mounted within said shell, a fuse element mounted on said carrier with the ends of said element bent across the ends of said carrier, a pair of elongated rigid expandable members pressing against the respective ends of the element to form a contact therewith, and a pair of caps pressing said members inwardly and threaded to the respective ends of said shell, the expansion of said members due to heat causing them to press more tightly against said element and improve the contact therewith. 100 105 110

4. A fuse comprising, in combination, an insulating shell, a carrier of less length than said shell and mounted within said shell to form a pair of chambers at the ends thereof, a fuse element mounted along one side of said carrier, and means for connecting said element in circuit, said carrier having an internal chamber and a pair of vents on the side opposite to said element connecting said internal chamber with the respective chambers at the ends of the shell, the gas generated by the blowing of the element expanding in the internal chamber and passing to the chambers in the shell at points spaced from said element to prevent arcing. 115 120 125

5. A fuse comprising, in combination, an insulating shell, a carrier of less length than said shell and mounted therein, said carrier being hollow to form a primary expansion chamber and being spaced from the ends of said shell to form secondary expansion chambers therewith, a fuse element having its 130

blowing point positioned within said primary chamber, means for connecting said element in circuit, and venting means between said primary and secondary chambers for drawing the gas generated by blowing of the element away from said element to prevent arcing.

6. A fuse comprising, in combination, an insulating shell, a carrier of lesser length than said shell and mounted therein, a fuse element mounted on one side of said carrier and having its ends bent transversely across the respective ends of the carrier, and a pair of members abutting against the respective ends of said element for connecting it in circuit, said carrier having an internal chamber within which the element blows and having vents at the side thereof, the ends of said carrier deflecting the path of the escaping gas away from said members.

7. A fuse comprising, in combination, an insulating shell, a carrier mounted centrally within the shell and having a lesser length than said shell to form a pair of chambers at the respective ends thereof, said carrier having a pair of longitudinal grooves cut in opposite sides thereof and a central transverse slot opening into said grooves, a fuse element mounted in one of said grooves and having its ends bent across the respective ends of said carrier, the blowing point of said element being positioned in said slot, a bridge over the ends of said slot fitting within said shell, a pair of members for connecting said element in circuit abutting against the respective ends of said element and extending outwardly to the ends of said shell, and means adjustably mounted on said shell for holding said members in abutment with said element.

8. A fuse comprising, in combination, an insulating shell, a relatively short fuse element mounted within said shell, a pair of knife-blade terminals mounted at the respective ends of said shell, each terminal having an elongated and reduced integral portion extending into said shell and abutting against the end of said element in a longitudinal direction, and a pair of caps each rotatable on one of said terminals and threaded onto the end of said shell to hold said terminal in close contact with said element.

9. A fuse comprising, in combination, an insulating shell having an aperture in the side thereof, a carrier mounted within said shell and having a groove in its side, and a bridge overlying said groove, said bridge being made of a transparent material, a fuse element mounted in said groove with its blowing point underlying said bridge portion, and means for connecting the element in circuit, said bridge portion being positioned opposite the aperture in said shell to form a window through which it may be observed whether the fuse has blown.

10. A fuse comprising, in combination, an insulating shell, a carrier mounted within said shell and having a groove in the side thereof, and an element fitting snugly within said groove, the size of said element and said groove being different in each different range of capacity of fuses, said groove being so limited in size that the fuse cannot be assembled if two or more elements of a size normally fitting in said groove or an element of a larger range of capacity are placed in said groove.

11. A cartridge fuse comprising, in combination, an insulating shell, a fuse element mounted within said shell, and contact members extending into the shell from the ends thereof for connecting said fuse in circuit and adjustably attached to the ends of said shell to form a pressure contact with said element, the points of contact of said members with the element being nearer to the center than to the ends of the shell to prevent any heat generated at said points from affecting the ends of said shell.

12. A cartridge fuse comprising, in combination, an insulating shell, a fuse element mounted within said shell, rigid contact members extending from said element through the ends of the shell, and means attached to the shell for causing said members to press against the ends of said element, said members being made of a material having a substantially greater conductivity than said element and extending a substantial distance within the shell to prevent any heat generated within the element or at the points of contact between said members and the element from materially affecting the ends of said shell.

13. A fuse comprising in combination, an insulating shell, a carrier having a relatively short fuse element thereon mounted within said shell, a pair of terminals mounted at the respective ends of said shell, at least one terminal having an elongated rigid portion abutting against the end of said element in a longitudinal direction, and means to press said terminals into close contact with said element, said elongated portion having a greater expansion than the shell as the fuse temperature rises due to current therein whereby to increase the contact pressure with temperature rise in the fuse.

In witness that I claim the foregoing I have hereunto subscribed my name this 5th day of June, 1929.

NORMAN M. STEPHENSON.
